(57) **CLAIM**

The ornamental design for a glass holder, as shown and described.

DESCRIPTION

FIG. 1 is a front perspective view of a glass holder that includes a back plate and further showing four glasses installed in phantom.

FIG. 2 is a front perspective view of the glass holder in FIG. 1 that includes a back plate.

FIG. 3 is a front view of the glass holder in FIG. 1 that includes a back plate.

FIG. 4 is a rear view of the glass holder in FIG. 1 that includes a back plate.

FIG. 5 is a top view of the glass holder in FIG. 1 that includes a back plate.

FIG. 6 is a bottom view of the glass holder in FIG. 1 that includes a back plate.

FIG. 7 is first side view of the glass holder in FIG. 1 that includes a back plate; and,

FIG. 8 is second side view of the glass holder in FIG. 1 that includes a back plate.

The broken lines showing the wine glasses are for illustrative purposes only and form no part of the claimed design. The glass holder is shown with a symbolic break in its back plate. The appearance of any portion of the article between the break lines forms no part of the claimed design.

1 Claim, 2 Drawing Sheets
